UNITED STATES PATENT OFFICE.

WILLIAM WIGG, OF LONDON, ENGLAND, ASSIGNOR TO LANSTON MONOTYPE MACHINE COMPANY, OF PHILADELPHIA, PENNSYLVANIA, A CORPORATION OF VIRGINIA.

TYPGRAPHIC COMPOSING-MACHINE.

1,307,718.

Specification of Letters Patent. Patented June 24, 1919.

Application filed December 5, 1917. Serial No. 205,615.

To all whom it may concern:

Be it known that I, WILLIAM WIGG, a subject of the King of Great Britain, residing at #104 Park avenue, Mitcham, in the 5 county of Surrey, London, E. C., England, have invented certain new and useful Improvements in Typographic Composing-Machines; and I do hereby declare the following to be a full, clear, and exact description 10 of the same, reference being had to the accompanying drawings, forming part of this specification, and to the characters of reference marked thereon.

This invention relates to machines for 15 composing or preparing patterns, record-strips or controllers, such as are employed to control the action of automatic type-casting and composing machines, each unit, character, symbol, or justification fraction being 20 set up or represented in the record-strip by one or more signal components or perforations through the instrumentality of key controlled punches or signal producing devices.

25 It has been usual, hitherto, to compose the line of matter so that when being cast the fractions necessary to justify the line have been added to certain predetermined "spaces" or space type-bodies which are variable in 30 set-wise measurement for justification purposes, as, for example, with the invention according to the U. S. patent to J. Sellers Bancroft and Mauritz C. Indahl, No. 944,405, dated December 28th, 1909, but it 35 has also been proposed, for example, according to the invention of the U. S. patent to the above inventors No. 1,094,630, dated April 28th, 1914, and of the pending application of Ernest Edward Sumner, S. N. 40 #139,628 filed December 29th, 1916, to add the justification fraction for a line to the "type" bodies, that is to say, to bodies of predetermined and fixed point sizes such as 45 characters, points, quads, etc., as distinguished from "space" type bodies and it is to machines so equipped that the present invention more particularly refers.

The signals for type are in general composed of two components, one denoting or 50 indicating position, the other position and dimensions, since in addition to determining in the casting machine the position of the

die or matrix, it also controls the dimensioning of the mold for the designated matrix, and the signal member or punch for producing this component is coupled with the line-measuring mechanism to effect the recording on the line measure of the unit value of each type; these components will be referred to hereinafter as positioning and dimensioning components respectively.

The dimensioning component of a space signal controls in the casting machine the setting or positioning of the normal mold-dimensioning mechanism as in the case of a type while the other component of the space signal controls the adjustment of a transfer mechanism which effects a change in the value of the normal mold-dimensioning mechanism when combined with a supplementary or justification mold-dimensioning mechanism as is the case when spaces are being cast, and the punch in the composing machine which produces the transfer component is coupled with mechanism whereby the line-measuring mechanism registers the unit value of the unjustified space at a fixed amount.

The signals for the justification fraction for the composed line are formed at the end 80 of the line and each comprises two components. As, however, in the organized casting machine the record-strip is passed therethrough in the order reverse to composition, the justification signals are presented at the record-strip interpreting mechanism of the casting machine before the signals denoting type and spaces.

These justification signals function in the casting machine to effect the adjustment or 90 setting of the supplementary mold-dimensioning mechanism which is only rendered operative to dimension the mold in conjunction with and in addition to the normal mold-dimensioning devices when spaces are being cast. The supplementary mold-dimensioning devices are rendered operative by the transfer component of the space signal which, as already stated, acts upon the transfer mechanism, while the setting of the normal mold-dimensioning devices is effected through the dimensioning component of the signal be it space or type.

With the above mechanism the dimension

indicated for any given position of the normal mold-dimensioning devices is two units less when controlled by the dimensioning component of a space signal than when controlled by the like component of a type signal, and as the same punch can be used for producing the dimensioning components of both kinds of signals, type and space, provision is made in the composing machine 10 whereby the register on the line-measuring mechanism will be two units less when recording a space than when used for a type.

In accordance with the invention described in Patent #1,094,630 and application #139,628, above mentioned, improved mechanism is provided for coupling at will the transfer component of the space signal with the type signals and for cutting out the unit registering or measuring mechanism of 15 the space signal, so that the unit value of the type signal will be registered; thus the signal, when being interpreted in the casting machine, will effect the setting of the normal mold-dimensioning devices and will also effect the coöperation therewith for dimensioning the mold for the designated type, 20 of the supplementary or justification mold-dimensioning devices.

The addition of this transfer component 25 to the type signal so that in the casting machine the mold is dimensioned by the joint action of the normal and supplementary or justification mold-dimensioning device diminishes the indicated value of the 30 designated type by two units, a deficiency which must be subsequently made up and applied through the medium of the justification signal which is increased in value to the extent of two units of the set for each 35 of the type signals to which the transfer component has been applied. It is the object of the present invention to eliminate the necessity of thus increasing the value of the justification signal by providing a device 40 for advancing the zero position of the line measuring mechanism, as will herein-after appear, as the result of which the value of type signals designated in company with the aforesaid transfer component are registered by the line-measuring mechanism two 45 units less in value than their normal dimensions, and further this device is operatively coupled with and is operated simultaneously with the mechanism for coupling the transfer component with the type signals. 50 By this means the correct justification fraction is shown on the justification indicator drum and all calculation by the operator and liability to error are eliminated.

Referring to the accompanying drawings: Figure 1 is a sectional elevation of part of a typegraphic composing machine embodying the present invention;

65 Fig. 2 is a perspective view of the mech-

anism for operatively coupling the transfer signal producing member with a type signal producing member and showing the device of the present invention, and

Fig. 3 is a front elevation illustrating 70 particularly the measuring mechanism of the machine shown in Fig. 1.

The composing machine to which the invention is herein shown applied and in connection with which it will be herein described is that of Patent #944,405, previously referred to, to the specification of which attention is directed for a full and complete description of the machine, it being sufficient for present purposes to 75 designate in general only those parts thereof with which the mechanism of the present invention is more intimately related, for example, (employing the same reference numerals as those of the patent,) the keys 80 180 pneumatically operating the punch bar motor pistons 29, connected with the punch bar levers 17 and punch bars 15, (the punch bar shown in Fig. 1 being that of the transfer or space punch); the line measuring 85 mechanism including the stop bars 13 on the outer ends of levers each operated from a dimensioning punch bar 15 through a lever 20 and a vertically movable bar 40; the units 90 rack 11 slidable in the units rack carrier 42 95 operated from the universal bar 19, the latter being connected by arms with the shaft 34 and by the arm 35 and link 36 with the return motor piston 37; the units wheel 7 and the line scale rack 14; the justification indicating mechanism identified by 100 the indicator drum 8 and the space counter or pointer 14*, the latter being carried by the vertical ratchet bar 85 driven upwardly by pawl and ratchet means including the 105 operating arm 91 and allowed to fall when desired by a suitably operated trip; the cushioning zero stop for the units rack comprising the bars 44 and 45.

The mechanism shown herein for coupling 110 the transfer signal producing member with a type signal producing member is similar to that disclosed in the Sumner application hereinbefore mentioned in accordance with which there is pivotally supported in a 115 bracket 71 (Fig. 2) secured to the machine frame, a lever 81 one end of which by a pin and slot connection is coupled with the transfer punch bar 15. To the other end of the lever 81 is pivotally connected, at a 120 point intermediate its ends, a bar or rod 9. At its lower end the rod 9 is formed with a hook or slot 10, which when the rod is turned on its pivot 12 engages a pin 16 on the arm 35 of the universal bar 19 as shown 125 in full lines in Fig. 1. In this position, when a key is operated to actuate the punches for a type signal, the universal bar 19 in rising, through its engagement with the shoulders on the punch-bars, acts to pull 130

down the rod 9, lowering the rear end of the lever 8¹ and raising its forward end to elevate and actuate the transfer punch bar 15 and its punch 1 independently of its motor. As the universal bar is actuated with each type signal, the transfer component will be added to all type signals so long as the rod 9 is coupled with the universal bar 19.

10 When the bar 9 is rocked or turned on its pivot 12 into the position indicated in broken or dotted lines in Fig. 1 and is thus uncoupled from the rod 16, then the transfer punch 1 will respond only to its motor 15 and be uninfluenced by the bar 19 as above described, and will then only operate as a component of a space signal.

As already stated, the transfer component punch 1 is coupled with the units stop pertaining to the space signal to effect the recording of the units value of the space signal, but when the transfer component of the space signal is added to the type signal, the unit value to be recorded is no longer 25 the constant value of a space signal but the variable value of a type signal, and, therefore, the units measuring mechanism of the space signal must be rendered inoperative so that the units will be measured from the 30 type signal, the unit stop for which is coupled with the dimensioning component or punch of the type signal.

The lever 20 connecting the punch bar 15 of the transfer component of the space signal punch 1 is coupled with the corresponding unit-stop-actuating bar 40, and for effecting the coupling and uncoupling of this stop, in accordance with this invention, the bearing 18 in the punch bar 15 for the 40 lever 20 may be opened and closed to form a detachable coupling. This bearing is formed in two parts which together embrace a rounded portion 21 on one end of the lever 20. The part 22 of the bearing is formed on 45 or in one with the punch-bar, but the lower part 23 is formed of a piece mounted to slide between guides formed on the bar, and is arranged to pass through an opening in the punch-bar.

50 When the movable part 23 of the bearing is in its forward or closed position the lever 20 is moved by the punch-bar and the units value of a space signal is recorded.

When, however, the transfer signal producing member is operated from the universal bar 19, the movable part 23 of the bearing is withdrawn to the position indicated in broken lines, Fig. 1, so that when the punch-bar is raised by the lever it rises without carrying with it the units stop operating lever 20 of the transfer component punch 1.

To facilitate the adjustment of the movable part of the bearing and to effect its adjustment simultaneously with the adjust-

ment of the punch-bar operating levers, there is coupled to the sliding part 23 a lever 24 which is pivoted to the lever 8¹ at 25 and is coupled at its upper end by a link 26 to the bar 9. The coupling shown is in the 70 form of a pin projecting laterally from the part 23 and normally seating between upturned wedge shaped prongs formed by providing the lower end of lever 24 with a fork and bending the prongs of the fork upwardly.

A spring detent 27 is provided and is adapted to engage with one or other of two notches 28, 29¹, on the sliding part to hold it in either of its adjusted positions.

The rod 9 is operated conveniently by a sliding bar 30 mounted upon studs 31, which are secured conveniently to the outside of the machine frame and pass through slots 32 in the bar. At its inner end the bar 30 has a downwardly extending slotted portion 33 which embraces a stud 36¹ on the upper end of the rod, and the slot 38 is sufficiently deep to accommodate and retain the stud in both of its positions of adjustment, 90 and when the rod 9 is reciprocated by the bar 16.

A spring detent 39 is secured to the machine frame and arranged to engage one or other of two notches 41, 42¹, in the bar to 95 retain it against accidental movement when in either of its adjusted positions.

In the class of machine to which the present invention refers there is a justification indicator 8 co-operating with the line-measuring mechanism from which the operator or compositor ascertains what keys it is necessary to operate to form in the record-strip the justification signals for the line, and co-acting with this indicator is a space counter 100 14¹ which is operated with each signal for a justification space. In the organized machine this space counter is operated by a motor, the air or operative fluid for which is supplied from the motor of the transfer component punch of the space signal.

When the mechanism is in operation for coupling the dimensioning signal producing members with the transfer punch, the latter is operated independently of its motor, and, therefore, the motor for the space counter will not be energized; it is accordingly necessary that the space counter be operated with each type signal with which the transfer component punch is coupled as otherwise 115 the fraction presented by the justification indicator would be inaccurate.

A convenient method of operating the space counter comprises a lever 43 which is pivoted intermediate its ends to the machine frame at 43^a. One end of this lever is connected by a link 43^b to the operating arm 91 for the space counter which is normally operated by the space counter motor. The other end of the lever 43 is connected by a 120 125 130

link 46 with the rod 9 which is capable of being coupled with so as to be operated by the universal bar.

Each time the rod is raised by the universal bar the lever will be actuated to lift the space counter one division.

In accordance with the present invention the zero stop device for the units rack is slidably as, for example, by securing the 10 block 44^a retaining the bars 44 and 45, by a pin and slot connection to the machine frame. As shown the block 44^a is provided with slots 44^b through which bolts 44^c extend into the frame. The adjustment of the block 15 is accomplished by the usual adjusting screw 45^a. A gag block 50 having two acting faces 50^a and 50^b situated in different planes and joined by an inclined or cam portion is positioned between the block 44^a and the screw 20 45^a and is capable of being moved vertically to present one or the other of its active faces between the block 44^a and the screw 45^a. When the face 50^b is presented to abut the rear end of block 44^a, the latter is in proper 25 zero position for normal operation, to which position it may be adjusted by operating the set screw 45^a. When, however, the gag block is moved downwardly, the block 44^a, carrying with it the bars 44 and 45 and the unit 30 rack 11, is moved in a direction toward the unit stops 13, by contact of the block 44^a with the inclined portion of the gag block. At the end of this downward motion of the gag block the face 50^a will bear against the 35 rear end of the block 44^a as shown in Fig. 3 and the zero stop mechanism will have been moved toward the stops 13, this movement amounting to two units because the face 50^a is formed two units in advance of the 40 face 50^b.

In this down position of the gag block, therefore, the units rack is advanced two units with respect to its normal position and when on the operation of a key, the units 45 rack is raised into mesh with the teeth of the units wheel to determine the rotation of the units wheel in accordance with the stop of the series of unit rack stops 13 which has been raised, the recorded value of the 50 signal as measured by the advance of the line-measuring rack 14 will be two units less than normal.

The gag block 50 is carried in guides 51 in the machine frame and is moved vertically to shift the block into and out of operative position by the rod or link 52. As the block is moved down the inclined part thereof moves the slidable block 44^a forward, against the tension of the spring 53 one end 55 of which is secured to the block 44^a and the other end to the machine frame, until the face 50^a bears against the rear face of the block 44^a.

In order that the block 44^a may be operated simultaneously with the coupling up 60

or uncoupling of the transfer component with the type signal producing devices the rod 52 is connected to one arm of a bell crank lever 54 which is pivoted to the machine frame at 55 and has its other end connected to the operating bar 30 of the transfer component coupling mechanism.

When the bar 30 is pulled toward the operator (Fig. 1) the bell crank lever 54 is rocked to force the block 50 downwardly 75 to the position just mentioned; the same motion also couples up the transfer punch bar 15 and the justification space counter 14^x with the universal bar 19 and moves out of place the lower bearing member 23 for the 80 lever 20, whereby upon the depression of a character key, the normal character indicating punches are operated as well as the transfer indicating punch; the space counter is also operated; the transfer punch unit 85 stop is not operated; and because the unit rack is displaced two units toward the unit rack stop 13 operated in accordance with the character key struck, the line measuring devices will record two units less than the 90 normal value corresponding with said character key.

I claim:—

1. In a typographic composing machine provided with type signal producing devices, space signal producing devices, line measuring mechanism including a units rack, and means for operatively coupling a type signal producing device with a space signal producing device, and in combination 95 therewith a slidably mounted zero abutment for the units rack and a device connected with said coupling means for advancing the position of said abutment simultaneously with the coupling of the type and transfer 100 signal producing devices.

2. In a typographic composing machine provided with line measuring mechanism including a units rack, a series of signal producing devices including dimensioning signal producing members and a transfer signal producing member, a stop for the units rack normally connected with said transfer signal producing member, means for operatively coupling a dimensioning signal producing member with the transfer signal producing member and for simultaneously disconnecting the transfer signal producing member from its units rack stop, and, in combination therewith, a slidably mounted 110 zero abutment for the units rack and a device connected with said coupling means for advancing the position of said abutment simultaneously with the coupling of the dimensioning and transfer signal producing 115 members.

3. In a typographic composing machine provided with type signal producing devices, space signal producing devices, line measuring mechanism including a units 120

rack, unit stops operated in time with the type and space signal producing devices for arresting the forward movement of the rack, and means for operatively coupling a type signal producing device with a space signal producing device and in combination therewith means connected with the coupling means for determining the zero position of the units rack.

4. In a mechanism as specified in claim 3, 10 means for determining the zero position of the units rack, embodying an abutment with means for shifting the same into and out of operative position in unison with the movement of the means for coupling the type and 15 space signal producing means.

WILLIAM WIGG.
